UNITED STATES PATENT OFFICE.

JOHN BONTA, JR., OF BURGIN, KENTUCKY.

SHIPPING-CRATE.

SPECIFICATION forming part of Letters Patent No. 590,510, dated September 21, 1897.

Application filed April 19, 1897. Serial No. 632,835. (No model.)

To all whom it may concern:

Be it known that I, JOHN BONTA, Jr., a citizen of the United States, residing at Burgin, in the county of Mercer and State of Kentucky, have invented certain new and useful Improvements in Shipping-Crates; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to crates, and particularly to the class of knockdown folding crates; and the object of the invention is to provide a shipping-crate of such novel and peculiar construction and arrangement of parts that it may be set up and locked and knocked down and folded and locked.

A further object of the invention is to provide a locking means of novel and peculiar construction to be used whether the case is standing up or in folded position.

Other objects and advantages accruing from the special arrangement and combination of parts will be revealed in the description of the claims to follow.

In the accompanying drawings, forming part of this application, Figure 1 is a perspective view of my crate set up. Fig. 2 is a longitudinal section of Fig. 1. Fig. 3 is a longitudinal section of the crate folded. Fig. 4 is a perspective view of the locking-links.

The same numeral references denote the same parts throughout the several figures of the drawings.

The top and bottom portions of the crate are composed of top and bottom trays 1 and 2 of substantially the same depth.

Upon the outside of the top is secured a bead 3, having a cavity 4, engaged by a hand-ring 5 of the locking-bar 6, held to the top by staples 7. The ends of the bar 6 engage the loop 8 of the locking-link 9, which is loosely hung on the standard 10, secured to the ends of the bottom tray 2 and having a loop 10^a. This loop 8 passes through a slot 11 in the ends of the top crate 1 and extends suffi-

ciently above the surface of the top tray to receive the ends of the locking-bar 6 to lock the crate in set-up position.

The compartments, which may contain the usual cell-cases, are composed of four pieces 55 12, hinged together at 13, and fit and are locked between the top and bottom trays both in folded and set-up position by the said locking means hereinbefore described.

The two trays are locked together with the 60 two compartments folded flat within the trays by slipping the link 9 down from the end of the standards 10 until it lies within the bottom of the tray. Then the top tray is placed in position with the loop 10^a of the standards 65 passed through the slots 11, where it is engaged by the end of the locking-bar 6. To prevent the locking-bar 6 from turning and sliding out of place, the ring of the bar is forced into the cavity 4. To unlock the same, 70 the ring is turned out of the cavity and the bar pushed out of engagement with the locking-loops.

I do not wish to be understood as limiting myself in the use of or adaptability of my invention to the number of compartments or the size or shape of the crate; but,

Having thus described my invention, what I claim as new, and desire to secure by Letters Patent, is—

1. The combination with a shipping-crate having a top provided with a cavity and end slots, of means for locking the top comprising the standards fixed to the bottom of the crate, the links on the standards, and the locking-bar having a coil or loop forming a hand-ring and adapted to engage said cavity, as set forth.

2. A shipping-crate comprising the top and bottom tray portions, the top portion having 90 a cavity, and slots through its ends, a locking-bar slidably secured to the said top, and having a hand-ring to engage the cavity and lock the bar to the top, the compartments between said trays, and the standards and links 95 secured together and to the bottom of the tray and adapted to pass through the said slots to be engaged by the said bar to lock the crate in either folded or unfolded condition, as set forth.

3. A shipping-crate comprising a top tray having a cavity and end slots, a locking-bar slidably secured to the top of the tray, and having a portion adapted to engage the said cavity and to fix the bar to the top, a bottom tray secured to the top tray, the links loose on the standards and adapted to hang inside the crate, and the partition held by said two

trays and locked by said bar, standards, and links in either set-up or folded position. ¹⁰

In testimony whereof I affix my signature in presence of two witnesses.
